UNITED STATES PATENT OFFICE

PEYTON S. COLES, OF ATLANTA, GEORGIA

GARMENT HANGER

Application filed December 22, 1928. Serial No. 327,958.

Generically this invention relates to hangers, but it is more especially directed to the type known as dress or coat hangers adapted to support various types of wearing apparel.

5 An important object of this invention is the provision of a hanger of this character comprising a flexible non-slip supporting member adapted to support garments, including garments of light and flimsy material such as ladies' waists and the like.

A further important object is the provision of a hanger of this character comprising a horizontal member and a hook member secured thereto intermediate its length, and a 15 flexible spiral-like member, preferably of rubber or other anti-slip material, centrally supported by said hook member above the horizontal member and having its ends connected to the ends of the horizontal member 20 to provide a flexible element for preventing slipping disengagement of ladies' garments and the like when they are supported by said hanger.

25 A still further object of this invention is the provision of a hanger as above described and having the horizontal member formed of two hingedly connected sections foldable upon themselves and having means for securing said sections either in longitudinal 30 alignment or at any desired angle with respect to each other, whereby the angularity of the flexible supporting member is adjustable to support various types of garments without distortion to said garments, and likewise permitting the expeditious collapsing 35 of the hanger to a small compass when not in use.

40 With these and other objects in view, which will become apparent as the description proceeds, the invention resides in the construction, combination and arrangement of parts, hereinafter more fully described and claimed, and illustrated in the accompanying drawings, in which like characters of reference 45 indicate like parts throughout the several figures, of which:

Fig. 1 is a side elevation of my improved hanger;

50 Fig. 2 is a fragmentary detail view of one

end of the longitudinal member and flexible element;

Fig. 3 is a detail view of the hook member showing manner of supporting the flexible member; and

Fig. 4 is a side elevation of a modified form showing the horizontal member hinged to render the device collapsible.

Practice has demonstrated that the various types of hangers with which I am familiar have proven unsatisfactory by reason of cost of production and the prevalence with which light gowns and other ladies' wearing apparel become disengaged from the hanger with attendant damage to such garments, and it was to overcome such deficiencies, and to provide a hanger simple in design, manufactureable at a negligible cost, light in weight, and having a flexible non-slipping supporting member adapted to maintain all types of clothing in proper position thereon, under certain circumstances to maintain various garments in their normal shape, and to prevent their ready disarrangement irrespective of the type of garment, including light and flimsy articles of ladies' wearing apparel, that normally tend to slip off the hanger, that I designed the device forming the subject matter of this invention.

50 In the illustrated embodiment characterizing this invention there is shown a hanger A comprising a horizontal member, preferably constructed of wood, but which may be constructed of any desired material, and having a hook member B extending through said member central of its length or otherwise suitably secured thereto, formed with a shank 6, in the present instance formed of wire and twisted to form loop 7 at a point suitably spaced above the member 5 and extending upwardly and terminating in hook 8, adapted to engage a suitable support, as will hereinafter more fully appear.

55 A flexible supporting member C adapted to extend through the said loop 7, preferably formed of rubber or other non-slip material and twisted to form spiral flights 9 and having each of its ends secured to the respective ends of member 5 by clips 10 or 100

other suitable fastening elements, as will be clear without further description.

Although I have shown the supporting member C as preferably constructed from rubber so as to maintain the garments in non-slipping contact therewith and formed with spiral flights to present an uneven surface to further insure non-slipping of the garments supported thereby, it is to be understood that I do not limit myself to rubber, since in some instances it might be found expedient to employ other materials without departing from the principles of my invention.

With but a negligible increase in cost of production the hanger as above described may be made adjustable and foldable into a small compass for purposes of shipment, for use while traveling, and the like, by simply having the horizontal supporting member formed with two sections centrally hinged so as to enable the ready folding for purposes above described.

Fig. 4 illustrates a hanger identical to that above described, with the exception that the horizontal member 5^a is formed with two complementary sections 11 and 11^a respectively, with their inner ends complementally mortised, said mortised portions being centrally bored to receive the threaded bolt 12 for engagement with thumb nut 13, actuation of which adjustably secures the sections in any desired angular position with respect to each other, as shown by dotted outline 14, said sections 11 and 11^a being folded upon themselves when not in use, as shown in dotted outline 15. While not necessary to the proper functioning of the device, if desired, the outer ends of the sections 11 and 11^a may be formed with an upwardly extended rounded projection 16, which effects a more pleasing appearance when the sections are positioned as shown at 14.

It is thus apparent that in this form of device the flexible supporting member C^a not only acts as a spring to effect the ready collapsing of the device but by virtue of its resiliency automatically maintains its form irrespective of the angular adjustment of the sections 11 and 11^a and by virtue of the adjustability of said sections, the angularity of member C^a according to the particular requirements is effected. It is therefore apparent that this form is readily adjustable to different weights, sizes and types of garments, which is especially desirable in connection with the variety in ladies wearing apparel.

From the above it will be apparent that I have designed a hanger for clothing of great adaptability, simple in construction, manufacturable at a negligible cost, embodying a novel flexible supporting medium, and efficient for the purposes intended.

Although in practice I have found that

the form of my invention illustrated in the accompanying drawings and referred to in the above description as the preferred embodiment is the most practical and efficient; yet realizing the conditions concurrent with the adoption of my device will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claim:

A garment hanger comprising a horizontal member, a hook member, secured to the horizontal member intermediate its length, said hook member formed with a loop at a point vertically spaced from the horizontal member, a rubber supporting element adapted to extend through said loop with its ends connected to said horizontal member, the said rubber supporting element being formed with spirals throughout its length comprising a plurality of upstanding garment contacting surfaces, whereby garments supported thereon will not slip off.
